UNITED STATES PATENT OFFICE.

JONATHAN C. SHUTTLEWORTH AND CHARLES L. SHUTTLEWORTH, OF FAIRMONT, WEST VIRGINIA.

COMBINED CHAIR AND SWING.

1,010,812.

Specification of Letters Patent.

Patented Dec. 5, 1911.

Application filed March 6, 1911. Serial No. 612,578.

To all whom it may concern:

Be it known that we, JONATHAN C. SHUTTLEWORTH and CHARLES L. SHUTTLEWORTH, citizens of the United States, residing at 5 Fairmont, in the county of Marion and State of West Virginia, have invented a new and useful Combined Chair and Swing; and we do hereby declare the following to be a full, clear, and exact description of the invention, such as will enable others skilled in the art to which it appertains to make and use the same.

This invention relates to a new and useful combined folding chair and swing attachment.

The principal object of the invention is to provide a chair for babies or young children, capable of being attached to the back of a chair, as shown in the drawings, thus providing 20 a high-chair, and which may be folded into a small compass, so that the same may be stored away, or readily packed in a trunk or dress suit-case.

A further object of the invention is to provide a foldable portable chair, which may be attached to the ropes of a swing.

In the drawing, however, there is only disclosed one form of the invention, but in practical fields this form may require slight alterations, to which the applicants are entitled, provided the alterations are comprehended by the appended claim.

The invention comprises further features and parts hereinafter set forth, shown in the drawings and claimed.

Referring to the drawings:—Figure 1, is a view in perspective showing the foldable chair as applied to the back of a dining chair. Fig. 2 is a view in perspective showing the 40 foldable chair folded. Fig. 3 is a view in side elevation, of the chair, as utilized as a swing. Fig. 4 is a view in front elevation of the combined folding chair and swing, showing the sides folded in dotted lines.

Referring to the drawings 1 designates a dining chair, to the back 2 of which the foldable chair 3 is applied. This foldable chair comprises the approximately arranged vertical frame 4, which is rectangular in contour. Pivoted in the lower portion of the frame 4 to the sides thereof, by means of pins or bolts 5 are the strips or bars 6. Secured to the bars or strips 6 is the seat 7 of the foldable chair. The sides 8 of the 50 foldable chair comprise the upper and lower

bars or strips 9 and 10, and the vertical bars 11. The lower strips or bars 10 are hinged as at 12 to the seat 7, so that the sides may be folded upon the seat 7, as shown in dotted lines in Fig. 4 and full lines in Fig. 2. 60

The table 13 of the foldable chair rests upon the sides 8, as shown in Figs. 1 and 3, and is provided on its lower face with partial rotatable members (which are angular in form) 14. These members 14 are adapted 65 to be swung under and in engagement with the strips or bars 9, so as to hold the table in position. These members 14 and the table 13 also constitute means for holding the sides of the chair in vertical positions as shown in 70 Fig. 1. At the top portions of the sides of the frame 4 eyes 15 are provided, between which and the eyes 16 of the strips or bars 6 chains 17 are connected. These chains also pass through eyes 18 of the table 13, thus 75 providing means for holding the table anchored to the other structure of the chair, especially when the chair is folded. The members 14 are of spring material and are adapted to frictionally engage the strips or 80 bars 9, and by this arrangement the table 13 may be adjusted outwardly upon the sides of the chair, thus arranging the chains 17 in the position shown in full lines in Fig. 3, which will hold the seat 7 in a slight inclined 85 position as shown in full lines in Fig. 3. The upper portions of the sides of the frame 4 are provided with hooks 19, which are adjustable with relation to the frame 4. By arranging the hooks 19 adjustable, the chair 90 is rendered applicable to dining chairs having backs of different heights. The hooks 19 are held in adjusted positions by the members 20. The hooks not only act as means for suspending the foldable chair upon backs of 95 dining chairs, but also constitute suitable means, to which cables 22 of a swing may be connected, as shown in Fig. 3.

From the foregoing it is apparent that a novel form of portable folding chair has 100 been devised, and one which has been found to be practicable, simple and efficient in construction and cheap to manufacture.

The invention having been set forth, what is claimed as new and useful is:—

A portable folding chair comprising a rectangular frame, a seat pivoted in the lower portion thereof, sides having a plurality of notches and hinged to the seat and capable of folding toward one another upon the seat, 110

the seat being foldable within the rectangular frame, a table adapted to rest on the sides and having partial rotatable spring members on its under surface to engage the 5 notches of the sides for holding the sides in open positions, the table having eyes, and chains arranged angularly and connecting between the seat and the frame and passing through the eyes of the table, adjustable suspension means carried by the frame, the 10 table being movable outwardly on the sides, thus constituting means in conjunction with

the chains for arranging the seats at an angle, the partial rotatable spring members and the notches constituting means for holding the table so adjusted. 15

In testimony whereof we have signed our names to this specification in the presence of two subscribing witnesses.

JONATHAN C. SHUTTLEWORTH.
CHARLES L. SHUTTLEWORTH.
